UNITED STATES PATENT OFFICE.

JOHN WILLIS GARDNER, OF QUINCY, ILLINOIS.

GOVERNOR FOR STEAM-ENGINES.

No. 896,376.

Specification of Letters Patent.

Patented Aug. 18, 1908.

Application filed January 2, 1908. Serial No. 408,878.

To all whom it may concern:

Be it known that I, JOHN WILLIS GARDNER, a citizen of the United States, and a resident of Quincy, in the county of Adams 5 and State of Illinois, have invented certain new and useful Improvements in Governors for Steam-Engines; and I do hereby declare that the following is a full, clear, and exact description thereof, reference being had to the accompanying drawings, and to the letters of reference marked thereon, which form a part of this specification.

This invention relates to improvements in variable speed governors for steam engines, 15 and the invention refers more specifically to an improved construction for varying the resistance against which the governor balls or weights are thrown outwardly by centrifugal action to close or throttle the governor valve 20 and thereby vary the speed of the engine when driving an approximately uniform load or for maintaining an approximately uniform speed when driving varying loads.

The invention consists in the matters hereinafter set forth and more particularly pointed out in the appended claims.

As shown in the drawings:—Figure 1 is a side elevation of a speed governor made in accordance with my invention, showing the 30 governor valve chamber in vertical section. Fig. 2 is a vertical axial section of the governor mechanism above the valve chamber. Fig. 3 is a partial vertical section and partial elevation, showing a modification. Fig. 4 illustrates a modification of the device for varying the length of the governor valve stem.

In said drawings, A designates the valve casing provided with inlet and outlet 40 branches A¹ A², respectively, and A³ designates a vertically reciprocating valve closure, of the piston type, engaging a seat formed by upper and lower seat rings a mounted in the upper and lower walls of an 45 extension casing A⁴ extending into the valve chamber from the inlet branch A¹. The governor stand or frame comprises two lateral, upright members B B rising from and supported on the upper wall A⁵ of the valve 50 casing, a hollow head B¹ connecting the upper ends of said members, and an upright hollow standard B² seated at its lower end in the hollow head and rising therefrom. C C 55 designate upper and lower sleeves surrounding and having rotative bearing on said tubular standard and to said sleeves are piv-

oted the toggle levers c c¹ of the centrifugal weights or balls C² of the governor. The lower sleeve C¹ is vertically confined on the standard B² between the head B¹ of the 60 frame and a collar b surrounding said standard and itself, as herein shown, surrounded by a vertical flange of said lower sleeve. The upper sleeve C is adapted to slide vertically on said hollow standard, said sleeve 65 sliding downwardly thereon as the weights or balls C² are thrown outwardly by centrifugal action. D designates a spiral, expansively acting spring interposed between said upper and lower sleeves and against the 70 resistance of which the centrifugal weights are thrown outwardly. The said weight supporting sleeves and the weights carried thereby, as well as the spring D, are rotated through the medium of a gear-pinion E, 75 which surrounds and is fixed to the lower sleeve C¹, and a gear-wheel E¹ which is fixed to the inner end of a horizontal shaft E² that is rotatively mounted in a bearing bracket B³ stationary with the governor frame or 80 stand.

In accordance with my invention, the governor valve stem, through which motion is transmitted from the revolving centrifugally operated weights or balls to actuate 85 the valve to diminish the area of the steam passage through the valve, is so constructed that it may be shortened or elongated, as desired, within a limited range in such manner as to vary the effective resistance of the 90 spring against which the valve is closed, and thereby vary the speed of the engine or maintain a given speed with varying loads. In the present instance, this result is accomplished by raising or opening the valve as 95 the governor valve stem is shortened, and vice versa. Thus when the governor is adjusted to a high speed by shortening the governor valve stem, a greater extent of movement of the stem and valve is required 100 to close the valve, with the result of increasing the compression of the spring D and correspondingly increasing its resistance to the closing of the valve. The particular construction herein shown by which this 105 result is effected is as follows: The governor valve stem comprises an upper member F which extends axially through the head B¹ and the hollow standard B², a lower member F¹ which is connected with the valve A³ and 110 extends upwardly through a suitable stuffing box a¹ in the upper wall of the valve cham-

ber, and an adjustable connection between said upper and lower members, comprising a short connecting piece F^2 connected at its upper end with the upper member of the 5 stem and a nut F^3 which is connected with the lower member of the stem and is interiorly screw-threaded to engage exterior screw-threads of said connecting piece F^2 . As herein shown, said connecting piece F^2 10 is provided at its upper end with an axial socket in which the lower end of the upper valve stem member is seated, and a pin f , which extends transversely through the upper valve stem member and engages upwardly opening notches f^1 in the connecting piece at the sides of the axial socket therein, 15 prevents relative rotation of said parts.

The connection between the nut F^3 and the lower member F^1 of the governor valve 20 stem consists of a head f^2 on the upper end of said stem member which engages an upwardly facing, internal shoulder of the nut above a reduced opening in the lower end of the nut through which the lower stem 25 member extends, and said nut and stem member have screw-threaded connection with each other. The parts are additionally secured together by means of a pin f^3 which extends transversely through the nut and 30 said stem member. To the upper end of the upper stem member F is fixed a head f^4 , made of slightly less external diameter than the internal diameter of the sleeve C , and said head opposes the lower face of a plug 35 c^2 which axially enters the upper end of said sleeve C and has screw-threaded engagement therewith. The said sleeve rotates relatively to said stem member, and any suitable antifriction devices may be interposed 40 between said head f^4 and the plug c^2 . A spring device is provided which acts on said governor valve stem to normally hold the valve in its open position and the connecting piece F^2 engaged with the upper 45 governor valve stem member F . The spring device herein shown for this purpose is made as follows: G designates a two-armed lever which is fixed to the outer end of a short horizontal rock-shaft G^1 that is mounted at 50 its ends in suitable bearing lugs b^1 on the vertical members of the governor stand or frame at the level of said connecting piece F^2 . Fixed to the inner end of said shaft is an arm G^2 which is forked at its free end to 55 engage recesses formed on the laterally opposite sides of the connecting piece F^2 . G^3 designates a spring-pressed plunger contained partially within a socket b^2 formed in a horizontally enlarged portion b^3 of the 60 governor stand or frame. Said plunger engages at its outer end a notch in the inner face of the upper arm of the lever G , and it is forced toward said arm by means of a spiral, expansively acting spring g surrounding the plunger and interposed between the

head of the plunger and an adjusting screw g^1 entering the rear end of said socket b^2 . The adjusting screw serves to vary the tension of the plunger spring to cause it to act with greater or less power to hold the valve 70 in an adjusted open position.

In the operation of the construction shown, the spring-pressed device just described serves at all times to hold the connecting piece against which it acts upwardly against 75 the upper member of the valve stem so that the valve will always respond promptly and accurately to the movement of the centrifugal weights.

The effect of adjusting the valve stem in a 80 manner to shorten it, in the construction herein illustrated, is to raise the valve in its seat and increase the area of steam passage therethrough. In proportion to the extent 85 that the governor valve stem is thus shortened and the valve raised or opened, a correspondingly increased movement of the valve stem and centrifugal weights is required to close or partially close the valve and a correspondingly increased compressing of the 90 spring D is effected. To a like extent is increased the resistance afforded by the spring against the action of the centrifugal weight to close or partially close the governor valve and in proportion as such resistance is, in 95 this or an equivalent manner, increased will the speed of the engine will be increased. Contrariwise, the lengthening of the governor valve stem has the effect to adjust the governor to a lower speed of the engine. 100

The said adjusting nut F^3 may be provided with finger lugs f^5 as indicated in Fig. 4, whereby the nut may be rotated to adjust the governor. If, however, the nut be located at an inaccessible position, or it is desired to adjust the governor from a distant point, I may employ the adjusting gear shown in Figs. 1 and 2 which is made as follows: H designates a sleeve which surrounds the nut and is rotatively mounted in a bearing b^4 made integral with the upright members B of the governor stands. Said sleeve is formed at its lower end to provide a beveled pinion H^1 which meshes with a beveled gear wheel H^2 fixed to the inner end of a 110 horizontal shaft H^3 that is rotatively mounted in a suitable bearing b^5 on the governor stand. Said sleeve is formed with a bore which permits the nut to slide therethrough while preventing relative rotation of the 115 sleeve and nut. As herein shown, the nut has a polygonal exterior contour and the bore of the sleeve is similarly formed, but made larger in diameter. Thus it will be seen that rotation of the shaft H^3 operates, 120 through the gear-wheel and pinion mentioned, to rotate the adjusting nut F^3 in either direction, thereby providing means for adjusting the governor from a distant 125 point. 130

If it be desired to provide for an extreme wide range of speed in the engine, I may employ the construction shown in Fig. 3, wherein is provided an additional spring resistance which is brought into service after the valve has been partially closed from its full open position, so that during the remaining travel of the governor valve stem to close the valve, the accumulative resistance of two springs is employed, thereby greatly increasing the speed of the engine. This result may be conveniently accomplished by providing an additional or auxiliary spiral spring I, surrounding the tubular standard B² of the governor stand or frame and located within the spring D before mentioned. When the auxiliary spring is employed, a ring I¹ is seated in an upwardly opening recess in the upper end of the lower rotative ball carrying sleeve B² against which the lower ends of both of said springs D and I bear. A similar ring I² may be placed on the upper end of the auxiliary spring to receive the direct contact of the lower end of the upper ball supporting sleeve C, when said sleeve is forced downwardly by the outward throw of the centrifugal weights. It will be observed that in the normal or inoperative position of the parts, said lower end of the sleeve C is located a distance above the upper end of the spring I, so that during the first portion of the downward travel of said upper sleeve and the governor valve stem, the resistance due to the spring D only opposes such downward movement. When, however, the lower end of the sleeve C strikes the ring I² of the auxiliary spring, the combined resistances of both springs oppose the further descent of the parts. Such auxiliary resistance is utilized when the governor valve stem is adjusted for high speed and operates, in conjunction with the adjustment of the governor valve stem, to produce and maintain the maximum speed of the engine at the time the said stem is adjusted to its minimum length.

In the above description reference has been made to adjusting the governor to vary the speed of the engine, such variable speed being predicated on an approximately uniform load and steam pressure. It will be understood, however, that the same construction may be employed for maintaining a substantially uniform speed of the engine where the load which the engine drives varies through a limited range.

The construction herein shown illustrates one approved embodiment of my invention, but it will be obvious that the same results may be secured in substantially the same manner by other embodiments of the invention differing in structural details from the construction herein specifically described.

I claim as my invention:—

1. In a speed governor, the combination of the governor valve, a governor valve stem, 65 a centrifugal weight arranged to act through the stem to close the valve, and a spring arranged to oppose the action of said weight to close the valve, said valve stem comprising upper and lower members and a rotative adjusting nut connecting the same, an adjusting hollow pinion surrounding said nut, and with respect to which the nut is endwise movable, and a pinion meshing with said adjusting pinion and fixed to a shaft which is 70 rotatively mounted on a fixed part of the governor stand.

2. In a speed governor, the combination of the governor valve, a governor valve stem, a centrifugal weight arranged to act through 80 the stem to close the valve, and a spring arranged to oppose the action of said weight to close the valve, said valve stem comprising upper and lower members and a rotative adjusting nut connecting the same, and means 85 for rotating said nut to adjust the length of said stem comprising a sleeve through which said nut loosely extends arranged to rotate the nut, a gear on said sleeve and an operating shaft provided with a gear meshing with 90 said sleeve gear.

3. In a speed governor, the combination with the governor valve, a governor valve stem, a centrifugal weight operating through said stem to close the valve, and a resistance 95 element arranged to oppose the action of said weight to close the valve, of means for varying the length of said governor valve stem and an auxiliary resistance element arranged to oppose the closing movement of the valve 100 due to said centrifugal weight during the latter part only of said closing movement.

4. In a speed governor, the combination with the governor valve, a governor valve stem, a supporting frame or stand, two 105 sleeves revolvably mounted on said frame, one of which is movable towards and from the other, centrifugal weights connected by levers with said sleeves, a spring interposed between said sleeves to oppose the movement of the weights to close the valve through said stem, and a second spring also interposed between said sleeves and made shorter than the first spring, for the purpose set forth.

115

In testimony, that I claim the foregoing as my invention I affix my signature in the presence of two witnesses, this 28th day of December A. D. 1907.
